UNITED STATES PATENT OFFICE.

WOIDEMAR HEINZ, OF DRESDEN, GERMANY.

CASH-REGISTER.

SPECIFICATION forming part of Letters Patent No. 885,151, dated March 11, 1902.
Application filed March 5, 1901. Serial No. 49,660. (No model.)

To all whom it may concern:

Be it known that I, WOIDEMAR HEINZ, a citizen of the Kingdom of Saxony, and a resident of Dresden, Germany, (whose post-office address is Bergmannstrasse 23,) have invented certain new and useful Improvements in Cash-Registers, of which the following is a specification.

The present invention relates to cash-registers or check-tills in which keys correspond to figures representing the sum of the purchase are operated, and a crank is then turned, whereupon figures indicating the said sum appear on that side of the apparatus turned toward the purchaser, and at the same time printing-types of the same figures are adjusted in the printing position and printed.

In the annexed drawings, Figure 1 represents a vertical section of the apparatus with its parts in the normal or "naught" position. Fig. 2 shows the position of the parts with the ninth key depressed and the crank somewhat removed from its normal position. Fig. 3 represents a section of the apparatus on the line A A of Fig. 1. Figs. 4 and 5 show the means for automatically disengaging and engaging the naught-key by means of the other keys.

In the case 1, inclosing the mechanism, the shaft 2 has bearing. The said shaft is operated by a crank 3. On the said shaft 2 is mounted a tappet 4, which on the rotation of the said shaft strikes against a driver 5, fastened to a shaft 6. Loosely mounted on the said shaft 6 are sleeves 7, which are prevented from moving longitudinally on the shaft and to which the segments 8, with numbers upon them, are fixed. The said number-segments can be moved past an opening in the case 1, through which they can be seen. Each of the said sleeves 7 also carries an arm 9, to which is fixed a segment 10 eccentric with the shaft 6 and serving to hold or lock the number-segments in the positions in which they are adjusted. To each of the said arms 9 is also fixed a segment 11, which carries the printing-type. At the side of each sleeve 7 a driver 12 is fixed to the shaft 6, which driver in moving about against a pin 13 on the arm 9, and thus raises the number-segment and the parts connected therewith.

At the end of the segment 10 farthest from

its supporting-arm 9 is a pawl 14 and at the end of the shaft 2 an eccentric 15. The latter acts upon a rectilinearly-guided slide 16, at the end of which is an inverted-V-shaped bar 17, adapted to engage the teeth 18 on the under side of the number-segments 10, and thus lock or hold the latter. A suitably-arranged helical spring 19 disengages the bar 17 from the said teeth whenever the smaller diameter of the eccentric 15 admits thereof. By the side of the eccentric 15 is another eccentric 20, which engages a link 21. The latter moves the printing arrangement (not represented in the drawings) toward the type.

In the case 1 of the apparatus a number of rectilinearly and radially guided keys 22 are arranged in rows of ten, each row representing the figures "0" to "9." To the side of each key a pin 23 is fixed, which enters the path of one of the before-mentioned pawls 14 when the key is depressed.

The action of the apparatus is as follows: Assuming that the ninth key of a row is depressed, as shown in Fig. 2, and the rotation of the crank has commenced, the maximum diameter of the eccentric 15 is moved from underneath the locking-slide 16, and the latter is forced downward by the spring 19, thus releasing the locking-segments 10 and the number-segments 8. The said segments thereupon descend, owing to their own weight, until the pawl 14 meets the pin 23, which has entered its path. In the meantime the driver 35 4 will have met the tappet 5, through which it will move the shaft 6. By means of the drivers 12 and the pins 13 the sleeves 7 are now also moved, and the number-segment 8, the locking-segment 10, and the type-segment 90 11 are thus moved upward again until the driver 4 has moved past the tappet 5. All the number-segments are then in their naught positions. As soon as the driver 4 has passed the tappet 5 the number-segment 95 3 again descend again until the pawl 14 meets the pin 23 on the key which has been depressed. When this occurs, the eccentric 15 causes the locking-slide 16 to engage the rack on the segment 10, so that no further movement of the number-segment can take place. At the same time the eccentric or cam 20 presses the printing device toward the type. The locking device also has the purpose of

fixing the numbers firmly and accurately in their position under the opening, through which they can be seen, in order to prevent inaccurate adjustment.

5. The apparatus is also provided with an arrangement which renders it unnecessary for the user of the till to depress the naught-key specially in registering amounts, the said naught-key being automatically operated.
10. As shown in Figs. 4 and 5, a slotted plate or slide 25 is movable on each of the plates in which the guides for the keys are arranged. To each of the said plates 25 a segment 26 is attached crosswise. Abutments 27 are fixed 15 at or near the lower ends of the keys, said abutments abutting against the segments 26, except in the case of the naught-key, on which there is no such abutment 27. If, for instance, the third key is depressed, Fig. 4, 20 the abutment 27 thereon forces the segment 26 and the slide 25 downward. The bifurcated end of the plate 25 engages the end of a double-armed lever 28, the other end of which is slotted and engages a pin 29, fixed to the naught-key. If, therefore, the segment 26 is moved 25 toward the center by the depression of any one of the keys, the naught-key is operated by the device described. Toward the end of each revolution of the crank the figures adjusted in the visible position are automatically removed. This is effected by eccentrics or cams 30, mounted on the shaft 2, which eccentrics or cams in rotating abut against inward projections on the plates 25 and force 35 the latter back. The cross-piece 26, also moving back, forces all keys outward, and thus renders the apparatus ready for use again. Simultaneously the inner end of the lever 28 is forced upward and the outer end 40 downward, whereby the naught-key is automatically set, and the latter remains so until another key is operated.

It is obvious that the apparatus described can be combined with a registering or reckoning apparatus by which all the figures registered are successively added. The construction of such reckoning apparatus may be of any suitable kind and forms no essential part of the present invention.

50. Having now particularly described and ascertained the nature of my said invention and in what manner the same is to be performed, I declare that what I claim is—

1. In a cash-register, the combination with 55 a plurality of keys; of indicating mechanism comprising a plurality of numeral-bearing segments movable independently to expose an amount, by gravity, the length of movement being controlled by the keys; a shaft forming the support for each segment, said shaft having means for moving said segments in opposition to the gravity movement; a rotatory shaft; and connections between said rotatory and supporting shafts for imparting said 60 opposing movement to the supporting-shaft.

2. In a cash-register, the combination with 65 a plurality of keys; of indicating mechanism

comprising a plurality of numeral-bearing segments movable independently to expose an amount, by gravity, the length of movement being controlled by the keys; a shaft forming the support for each segment, said shaft having radially-projecting pins; laterally-projecting pins carried by each of said segments adapted to be engaged by said radially-projecting pins; a rotatory shaft; and connections between said rotatory and supporting shafts for imparting a movement to said radially-projecting pins. 70

3. In a cash-register, the combination with 80 a plurality of keys; of indicating mechanism comprising a plurality of numeral-bearing segments movable independently to expose an amount, by gravity, the length of movement being controlled by the keys; a shaft forming the support for each segment, said shaft having radially-projecting pins; laterally-projecting pins carried by each of said segments adapted to be engaged by said radially-projecting pins; a rotatory shaft; and 85 connections between said rotatory and supporting shafts and operating during a portion of the movement of said rotatory shaft, for imparting a movement to said radially-projecting pins. 90

4. In a cash-register, the combination with 95 a plurality of keys; of indicating mechanism comprising a plurality of numeral-bearing segments movable independently to expose an amount, by gravity, the length of movement being controlled by the keys; a shaft forming the support for said segments; a rotatory shaft; a driver carried by said supporting-shaft; and a tappet carried by said rotatory shaft, whereby a movement in opposition to the gravity movement will be imparted to the said segments. 100

5. In a cash-register, the combination with 110 a plurality of keys; of indicating mechanism comprising a plurality of numeral-bearing segments movable to a position to expose an amount, by gravity; a supplemental segment carried by each of the numeral-bearing segments, said supplemental segments carrying key-engaging means for limiting the gravity 115 movement of the numeral-bearing segments; a rotatory shaft operatively connected to impart a movement in opposition to said gravity movement; and means operated by said shaft and co-operating with the supplemental segments for locking said segments in position. 120

6. In a cash-register, the combination with 125 a plurality of keys; of indicating mechanism comprising a plurality of numeral-bearing segments movable to a position to expose an amount, by gravity; a supplemental segment carried by each of the numeral-bearing segments, said supplemental segments carrying key-engaging means for limiting the gravity movement of the numeral-bearing segments; 130 said supplemental segments also having a series of notches on their under sides; a rotatory shaft; a cam carried by said rotatory shaft; and a bar adapted to be moved into

contact with one of the notches of each of the supplemental segments by said cam, whereby said segments will be locked in position.

7. In a cash-register, the combination with 5 a plurality of keys; of indicating mechanism comprising a plurality of numeral-bearing segments movable to a position to expose an amount, by gravity; a supplemental segment carried by each of the numeral-bearing segments, said supplemental segments carrying key-engaging means for limiting the gravity movement of the numeral-bearing segments; a rotatory shaft operatively connected to impart a movement in opposition to said gravity 15 movement; a cam carried by said rotatory shaft; a rectilinearly-guided bar adapted to be moved into contact with one of the notches of each of the supplemental segments by said cam, whereby said segments will be locked 20 in position; and a spring operating in opposition to said cam.

8. In a cash-register, the combination with 25 a plurality of push-keys, each having a laterally-extending pin; of a segment having a pivotal movement; and a spring-actuated pawl carried by said segment, said pawl being adapted to contact with said pin when the key is depressed and said segments are moved to indicate the amount.

30 9. In a cash-register, the combination with a plurality of push-keys, each having a laterally-extending pin; of a segment having a

movement in one direction due solely to gravity, said segment having a pivotal movement; and a spring-actuated pawl carried by said 35 segment and adapted to contact with said pin when the key is depressed, said contact serving to limit the gravity movement of said segment and hold said key depressed.

10. In a cash-register, the combination with 40 a plurality of push-keys including a "naught-key," each of said keys having a pin; of a device by which the "naught-key" is automatically raised and depressed, said device comprising a slotted plate or slide adapted to be 45 displaced by the pins, said plate operating a double-arm lever, the free end of which acts upon the "naught-key" in a manner to displace the said key in the opposite direction to the slotted plate or slide. 50

11. In a cash-register, a plurality of number-segments adapted to be automatically adjusted by gravity and directly connected with the type-segments; automatic devices for locking and securing said number-segments 55 in their positions; and a "naught-key" connected with the other keys so as to be operated thereby, substantially as described.

In testimony whereof I affix my signature in presence of two witnesses.
